METHOD OF MANUFACTURING ROLLING CUTTERS FOR DRILLING PURPOSES

John A. Zublin, Los Angeles, Calif.

Application November 3, 1944, Serial No. 561,733

4 Claims. (Cl. 76—108)

This invention relates to a method of manufacturing rolling cutters for drilling purposes.

Rolling cutters are used particularly in the drilling of wells and are subjected to very great stresses.

In some instances, for example, in the employment of a turbine-driven gyrating rolling cutter, such as shown in my U. S. Patent No. 2,336,335, the inclined shaft which carries the cutter rotates under the action of the turbine at a speed of from 1,000 to 10,000 R. P. M. The cutter is sufficiently out of balance with respect to the turbine axis to set up tremendous vibration in the whole turbine, and the drill pipe immediately above the same. In the operation of such turbine-driven gyrating cutters, it is desirable to reduce the vibrations to a minimum, and this can best be accomplished by reducing the weight of the gyrating cutter.

Rotating cutters for this use can be machined from a solid block of steel only with great difficulty, particularly where special tooth designs are required. When machined from a solid block of steel, there is, furthermore, a substantial material loss in the cutting of the blades and teeth.

It is accordingly the object of the present invention to provide an expeditious method of manufacturing rotating cutters that is both economical of labor and material.

It is a further object of the invention to provide a method for manufacturing a rotating cutter adapted to mass production methods and capable of producing rotating cutters of light weight possessing maximum tensile and crushing strength.

It is a further and more specific object of the invention to provide an expeditious method for manufacturing rotating cutters from rolled alloy steel, particularly applicable to the production of small-size rotating cutters of intricate design.

Further and more detailed objects of the invention will become apparent as the description proceeds, which will be given in connection with the accompanying drawings which illustrate the steps of the method, and in which:

Fig. 1 is a view in side elevation of the machined cutter body;

Fig. 2 is a view in side elevation, partly in section, of a machined bowl employed in forming the blades of the cutter;

Fig. 3 is a cross-sectional view through the blade bowl showing the tooth forming channels therein;

Fig. 4 illustrates the step of cutting segments

from the blade bowl to provide an integral multi-bladed web;

Fig. 5 illustrates the manner in which short blades are cut from segments removed from the blade bowl;

Fig. 6 is a bottom plan view showing the integral multi-bladed web and the short blades assembled on the cutter body;

Fig. 7 is a detailed cross-sectional view on the line 7—7 of Fig. 6 through the finished rotating cutter, particularly illustrating the manner in which the multi-bladed web and the short blades are welded to the cutter body; and

Fig. 8 illustrates the adaptation of the method of the invention to a bladed cone rotating cutter.

In carrying out the method of the present invention, there is first fabricated from rolled alloyed steel by conventional machinery a rotating cutter body indicated at 10 in Fig. 1, having ball races 11 on its inner surface, which cutter body is adapted to be mounted upon a suitable shank. There is next produced what for convenience will be herein termed a "blade bowl" indicated at 12 in Fig. 2. This blade bowl 12 has an interior configuration conforming exactly to the exterior configuration of the cutter body 10. The exterior of the blade bowl 12 is first machined as a rotational body to provide a contour representing the desired extremes of the blades for the cutter. The blade bowl 12 may then be further machined as a rotational body to cut the annular tooth forming channels 13 therein as more specifically shown in Fig. 3.

At this point in the process of manufacture, appropriate segments are cut from the blade bowl to provide an integral multi-bladed web. In Fig. 4, the blade bowl 12 is shown with the outline of six blades and six intervening segments thereon, with one of the segments removed. The removed segment of Fig. 4 is indicated by the reference character 14 and, of course, has in its exterior surface the same tooth forming channels 13 cut therein when the segment 14 constituted a part of the bowl 12. The segment 14 or a similar segment cut from the bowl 12 is adapted to be cut up into smaller segments as indicated at 15 in Fig. 5, each segment 15 constituting an individually radially short blade having, however, an interior configuration conforming to the exterior configuration of the rotating cutter body 10.

When all of the segments are cut from the blade bowl 12, there is provided an integral multi-bladed web, more particularly shown in Fig. 6, and which is held together at the central por-

tion 16 from which the blades 17 extend outwardly and upwardly. The integral multi-bladed web thus formed from the blade bowl 12 fits accurately and snugly over the rotating cutter body 10, and the blades 17 are each welded to the cutter body 10 as indicated at 18 in Fig. 7. At this point the rotating cutter body 10 and the integral multi-bladed web formed from the blade bowl 12 are integrally united into a unitary multi-bladed rotating cutter structure. This rotating cutter structure thus produced is capable of many uses in this form. It will be readily appreciated that the teeth of the blades may be sharpened, appropriately heat-treated, and provided with hard surfacing as desired before or after the integral multi-bladed web is welded to the rotating cutter body 10.

It has been found highly advantageous to provide the rotating cutter with supplemental blades of less radial extent than the blades 17. To achieve this result, the radially short blades 15, formed from a segment such as 14 cut from the blade bowl 12, are welded to the rotating cutter body 10 as more particularly shown at 19 in Fig. 7. In this way, the finished rotating cutter, having alternating long and short radially extending blades, is produced with a minimum requirement of both material and labor.

It will be observed that the rotating cutter thus produced is especially well adapted for use in drilling wells where a circulating mud fluid is employed, since the cutter is provided with extensive open areas through which the circulating fluid may pass. To facilitate such flow of circulating fluid and minimize wear on the central portion 16 of the rotating cutter, a stream-lined flow dividing member 20 may be welded on the upper side of the central portion 16 as shown in Fig. 7.

The same method hereinabove described is equally applicable to the production of multi-bladed rotating cone cutters such as exemplified in Fig. 8. In this figure, the rotating cutter body 21 is cone-shaped rather than cylindrical. The integral multi-bladed web 22 is, in this case, produced from a blade bowl having a conical interior surface rather than a cylindrical surface, such as illustrated for the blade bowl 12 in Fig. 2. It will be appreciated that the same steps are performed in the same sequence in producing the structure of Figs. 6 and 7.

From the foregoing it will be apparent that I have provided a novel method for producing light-weight rotating cutters from such materials as rolled alloyed steel without the necessity of expensive equipment and through the employment of procedure adapted to the use of automatic machines. Additionally, I have provided a method for producing a rotating cutter and a

multi-bladed web which may be fitted accurately, ensuring a good weld and a rigid system of body, blades, and teeth, equal in strength and performance to a cutter machined in one piece from a solid block of steel. The novel method of the instant invention enables the production of high quality rotating cutters with a saving of as much as 50% in material and a like or greater saving in labor over conventional manufacturing methods.

Having thus described my invention, what I claim is:

1. A method of manufacturing a rolling cutter for drilling purposes comprising machining a cutter body for rotation on a shaft, machining as a rotational body a bowl to provide the same with an interior configuration conforming to the exterior configuration of said cutter body, cutting segments from said bowl to provide an integral multi-bladed web, and welding said multi-bladed web on said cutter body.

2. A method of manufacturing a rolling cutter for drilling purposes comprising machining a cutter body for rotation on a shaft, machining as a rotational body a bowl to provide the same with an interior configuration conforming to the exterior configuration of said cutter body, cutting segments from said bowl to provide an integral multi-bladed web, welding said multi-bladed web on said cutter body, cutting individual radially short blades from the said segments and welding a short blade to said cutter body intermediate the blades of said multi-bladed web.

3. A method of manufacturing a rolling cutter for drilling purposes comprising machining a cutter body for rotation on a shaft, machining as a rotational body a bowl to provide the same with an interior configuration conforming to the exterior configuration of said cutter body and with a plurality of annular tooth-forming channels on the exterior thereof, cutting segments from said bowl to provide an integral multi-bladed web, and welding said multi-bladed web on said cutter body.

4. A method of manufacturing a rolling cutter for drilling purposes comprising machining a cutter body for rotation on a shaft, machining as a rotational body a bowl to provide the same with an interior configuration conforming to the exterior configuration of said cutter body and with a plurality of annular tooth-forming channels on the exterior thereof, cutting segments from said bowl to provide an integral multi-bladed web, welding said multi-bladed web on said cutter body, cutting individual radially short blades from the said segments, and welding a short blade to said cutter body intermediate the blades of said multi-bladed web.

JOHN A. ZUBLIN.
